CLIFFORD W. ASHLEY, OF WILMINGTON, DELAWARE.

SENNIT OF POLYGONAL CROSS-SECTION.

1,361,803.

Specification of Letters Patent. Patented Dec. 14, 1920.

Application filed January 14, 1919. Serial No. 271,020.

To all whom it may concern:

Be it known that I, CLIFFORD W. ASHLEY, a citizen of the United States, residing at Wilmington, county of New Castle, State of Delaware, have invented certain new and useful Improvements in Sennits of Polygonal Cross-Sections, of which the following is a specification.

My invention relates to sennit or cordage 10 plaited from a plurality of strands and more particularly to sennits of which the cross section is polygonal instead of circular or other curved contour.

My invention not only includes sennits 15 having a variety of novel polygonal sections but also a novel method of making such sennits.

By my improved method I am able not only to make a new four-sided sennit (*i. e.*, 20 sennit of rectangular section) although, broadly speaking, a four-sided sennit *per se* is old, but I am also able to make a sennit whose section is a triangle, a pentagon, a hexagon, or, in fact, any polygon regardless of the number of sides.

In the product turned out by my improved method, the several sides of any given type of sennit will be of uniform dimension, *i. e.*, the sides of a cross section will have the same 30 breadth.

The sennits of my invention may be given a section of any desired size and may be made of any desired length.

When my improved sennits are of small 35 cross section they are very attractive in appearance and may be used to advantage in many arts to secure ornamental effects. This is especially the case if the strands from which the sennits are plaited are suitably 40 and differently colored.

Perhaps the most important of the several sennits of my invention is the one whose section is an equilateral triangle. So far as I know, such a triangularly-sectioned sennit 45 is absolutely unique in the art. It may be used to great advantage mechanically in "rope drives" since, thereby, two-thirds of the area of the sennit may be brought into frictional engagement with the co-operating 50 pulleys instead of something less than one-half of the area, as in the case of a circular sennit.

My invention will be better understood by referring to the accompanying drawings 55 which are directed to a nine-strand sennit whose section is an equilateral triangle, this

being a preferred embodiment. Of these figures, Figure 1 represents a perspective view of the strands after they have been fastened together at one end but before any 60 actual plaiting has been done; Fig. 2 is a plan view, taken from above of Fig. 1; Fig. 3 represents a view of the sennit taken "edge (or corner) on," *i. e.*, from squarely in front of an apex of the section; Fig. 4 represents 65 another view of the sennit taken from the side; and Fig. 5 represents a cross section through the completed sennit.

To make the sennit, I first fasten all the strands together at one end in any convenient 70 way. As represented, they are shown as ending in a spool and separated by definite spaces, but this has been done merely to avoid confusion in description and to make the portions of the strands which are to be 75 manipulated stand out clearly. In practice, the ends need only be bound or held together in any convenient way, *e. g.*, as shown in Figs. 3 and 4.

Three strands, 1, 2, 3, which may be designated as "side strands," are drawn out upwardly (Fig. 1). The remaining strands are divided into three groups of two strands each, viz., the A, the B, and the C groups (A, a; B, b; and C, c); these may be called 85 "corner strands." The corner strand groups are drawn downwardly over the edge of the spool, being separated from one another by the side strands. The whole may then be grasped in the palm of the left hand with 90 the side strands, 1, 2, 3, passing up and draping over the forefinger while the corner strands, A, a, B, b, and C, c, pass out at the bottom of the hand.

First half-cycle.—Facing side strand 1, 95 pass it over corner strands C, c next adjacent on its left and then down into the palm; grasp corner strands C, c and draw them straight up so as to drape over the forefinger with side strands 2 and 3.

Now rotate the whole in the palm so as to face side strand 2 (clockwise); cross this strand over corner strands A, a at its left and then down into the palm; then raise corner strands A, a and drape over the forefinger.

Again rotate the whole clockwise so as to face side strand 3, pass it to the left over corner strands B, b and raise these corner strands and throw them over the forefinger.

This completes the first half-cycle. The three side strands will now all pass down-

wardly through the palm while the six corner strands will have replaced the side strands and will extend upwardly over the forefinger.

5 *Second half-cycle.*—Facing (the new position of) side strand 1 again, pass the nearer of the corner strands (this will be strand B) at its left, to the right over the side strand and drop it into the palm, raise the side 10 strand over the forefinger and then drop the remaining corner strand *b* into the palm.

Rotate the whole counter-clockwise until facing (the new position of) side strand 3, then pass corner strand A at its left, to the 15 right, across the side strand and into the palm where it will lie side of corner strand *b*, then raise and extend side strand 3, and finally drop corner strand *a* into the palm.

Again rotate the whole until facing (the 20 new position of) side strand 2, then pass corner strand C at its left, to the right, across the side strand and into the palm where it will lie side of corner strand *a*, then raise and extend side strand 2, and finally 25 drop corner strand *c* into the palm where it will lie side of corner strand B.

This completes the second half-cycle and brings the strands back into the original starting position with the three side strands 30 extending upwardly and the corner strands in three downwardly extended groups. The specific strands, as numbered in the figures, will not, however, occupy the same relative positions but will be changed about, although, disregarding the numbering, the positions of side strands and corner strands 35 will remain relatively unchanged.

The entire operation (first and second half-cycles), as above described, may now be 40 repeated indefinitely until the desired length of sennit has been secured.

After the first cycle has been completed, it will be found that, at the beginning of each succeeding second half-cycle, the corner 45 strands will lie in two tiers, *i. e.*, of each pair one will lie above the other. Then and thereafter, it is the lower strand which is, in each case, to be laid to the right over the side strand while the upper strand is to be 50 dropped straight down into the palm.

In describing the plaiting as above, the procedure has been minutely specified in order that the unpractised may have no excuse for error. In practice, it will be found 55 immaterial whether the inchoate structure be revolved clockwise or counter-clockwise in performing the operations of the first half-cycle and the same will be true as to the second half-cycle. The order of proceeding 60 will also be immaterial; *i. e.*, in the first half-cycle, any side strand may be the first to be chosen to pass over the corner strands at the left and then either the side strand to the one side or the other may be chosen 65 as the next to be manipulated. And, when

the first half-cycle is completed, any pair of corner strands may be chosen as the first to operate upon and after the one has been laid to the right, the side strand raised, and the remaining corner strand dropped into the 70 palm, the next and second pair of corner strands to be manipulated may be either the pair to the one side or the other.

It will be noted that, in the finished sennit, the three pair of corner strands lie above 75 one another in the same relative order as that of their adjacency when the manipulations of the first half-cycle are gone through with and that this order is maintained throughout the entire sennit. It should also 80 be noted that the side strands lie similarly one above the other but that their direction is transverse to that of the corner strands which are individually crossed by the side strands in the middle of each side.

85 I may give my improved sennit a quadrangular, pentagonal, hexagonal or any other desired regular polygonal section by merely adding a pair of corner strands and a side strand for each additional side desired 90 and following exactly the same rule of construction as has been above set forth.

Many interesting variants of the above referred to sennits may readily be produced within the spirit of the invention. Thus instead of having two corner strands to a set or side, three (or more) may be used. The procedure will be exactly as before except that the newly added strand will always be kept alongside the last to be manipulated of 100 its associated corner strands (*i. e.*, alongside the corner strand which is to be dropped in the palm in the second half-cycle) and manipulated with it. The characteristics of this sennit will be exactly the same as those 105 of the nine strand sennit except that there will now be three sets of three, instead of three sets of two, corner strands arranged one above the other and running continuously around the sennit in the same direction 110 throughout its length.

Similarly, the number of side strands may be increased. Thus I may make a triangular sectioned sennit with nine corner strands (three sets of three each) instead of six 115 (three sets of two each) as illustrated, and six side strands (three sets of two each) instead of three (three sets of one each). In such case, I manipulate and treat each set of side strands as a single strand.

120 If desired, a core may be used to increase the diameter or cross-section of any of the above referred to sennits; it will be understood however, that the core contributes nothing to the structure other than a filling 125 and that it is in no way necessary to the actual plaiting of the sennit or in the determination of its cross-sectional form.

Having described my invention, I claim:
1. A sennit of polygonal cross-section 130

and devoid of a form defining core comprising side strands and corner strands, the corner strands and side strands being at right angles to one another and the side strands crossing the corner strands in the middle of each side, said sennit depending for its cross-sectional form entirely upon the correlation of the strands without the assistance of a core or the like.

10 2. The method of making a sennit of polygonal cross-section and devoid of a form defining core which comprises arranging a plurality of strands in three or more similarly disposed groups, each group consisting of at least one side strand and of at least two corner strands, extending the side strands upwardly and extending the corner strands downwardly, passing successively each side strand group over the adjacent corner strand group at its left and dropping said side strand group downwardly and then extending the corner strand group upwardly, then passing successively the nearer strand of each

corner strand group over the side strand group at its right and dropping it downwardly, then extending the side strand group upwardly and dropping the remaining strands of the corner strand group downwardly, thus completing a cycle and repeating the cycle as many times as may be necessary to secure the desired length of sennit.

3. A sennit of triangular cross-section and devoid of a form defining core comprising corner strands which pass spirally about the apices and across the sides of the sennit in one general direction and side strands which pass spirally in the opposite direction and lie beneath said corner strands at said apices and above the same at the faces of said sennit, the correlation of the strands alone determining the cross-sectional form of the sennit.

In testimony whereof I have hereunto set my hand.

CLIFFORD W. ASHLEY.
